UNITED STATES PATENT OFFICE.

RUDOLPH CHARLES MILLER, OF BEAUMONT, TEXAS.

GRAIN-DOOR FOR CARS.

1,017,786.

Specification of Letters Patent. Patented Feb. 20, 1912.

Application filed December 23, 1910. Serial No. 598,964.

To all whom it may concern:

Be it known that I, RUDOLPH C. MILLER, a citizen of the United States, residing at Beaumont, in the county of Jefferson and State of Texas, have invented certain new and useful Improvements in Grain-Doors for Cars, of which the following is a specification.

My invention relates to new and useful improvements in doors for grain cars.

The object of the invention is to provide a door through which grain or similar contents may be readily unloaded from a car or bin or other container of like character.

With the above and other objects in view my invention has particular relation to certain novel features of construction and operation an example of which is given in this specification and illustrated in the accompanying drawings, wherein:—

Figure 1 is a side elevation of the door, showing also the adjacent parts of a freight car. Fig. 2 is an edge view of the door showing the adjacent parts of the car in section, taken on the line *a—a* of Fig. 1. Fig. 3 is a perspective view of the car door showing the same open for the discharge of the car contents. Fig. 4 shows a sectional view of the door taken on the line *b—b* of Fig. 3. Fig. 5 is an enlarged sectional view of a portion of the door taken on the line *c—c* of Fig. 1 and showing the shutter and the folding aprons in closed position.

Referring now more particularly to the drawings, wherein, like numerals of reference designate similar parts in each of the figures, the numeral 5 refers to the car wall provided with the usual side opening through which the contents of the car are loaded. This opening is closed in the usual manner by means of the ordinary slide door 6. In addition to this door I have provided my improved door to be used when the car contains such grains as wheat, oats, etc., or fruits or vegetables or similar contents. This door is swung from within the car in the manner presently to be described.

Near the top of the car wall and on the inner side thereof I have secured suitable hinge members 7 to which the supporting frame 8 is hingedly secured. This frame comprises two downwardly extending rods, one on each side of the door, united at their lower ends by a cross rod, as shown in Fig. 3. The numeral 9 designates the improved door proper which is suspended on frame 8

by means of bearings 10 which are secured to said door and are vertically slidable on said rods. When the door is not in use it may be elevated on its supporting frame and 60 bodily folded up to the top of the car and there secured by means of hook 11, which depends from the car roof and is disposed so as to readily engage over the bottom end of the door when so folded. The bottom 65 portion of this door is provided with a discharge opening centrally located with respect to the sides thereof and provided for the discharge of the car contents and secured upon the outside of the door and on 70 each side of the discharge opening is an upright cleat 12, the inner side of which is provided with lengthwise grooves 13 and 14 for a purpose hereinafter set forth.

The numeral 15 refers to a shutter which 75 is hinged to the door at the points 16, and which when shut closes the discharge opening of door 9. The shutter may be secured in its closed position by means of hooks 17, carried by the door and arranged to engage 80 in staples 18, carried by the shutter. The shutter is provided with folding aprons, of sheet metal one on each side, composed of the members 19 and 20. The members are hinged together along the line 21 and the 85 members 20 are hinged to the sides of the shutter along the line 22. The free edge of each member 19 carries an outwardly projecting rib 23 which fits into groove 13 of cleats 12, as shown in Fig. 3, when the 90 shutter is open and secures the aprons to the door.

It is sometimes desirable to shut off the discharge of the car contents before the car is entirely unloaded and for this purpose I 95 have provided the slide gate 24 which is freely slidable in grooves 13 which extend the full length of the cleats 12. The lower portion of each side of this gate is inwardly shouldered, as at 25, so that the lower edge 100 thereof may fit down between the apron members 19 and firmly secure the ribs 23 in grooves 13, when shutter 15 is open for the discharge of the car contents. When it is desired to cut off the discharge entirely the 105 ribs 19 are removed from grooves 13 and placed in grooves 14 of cleats 12 as shown in Fig. 4 and the slide gate 24 then entirely closed. When it is desired to close shutter 15 the gate 24 is elevated and the aprons of 110 the shutter are folded first along line 21 the rib 23 falling between the members 19

and 20 and said members being folded then against said shutter, as shown in dotted lines in Figs. 1 and 5, and the shutter then secured closed, as shown in said figures.

5 It will be observed that the aprons serve the double purpose of supporting the shutter when the same is open and the grain is passing thereover, and also form the sides of a discharge chute of which the shutter itself 10 forms the bottom.

What I claim is:—

1. A device of the character described including a door having a discharge opening therethrough, a closure for said opening, 15 foldable aprons hingedly secured to each side of the closure and detachably secured to said door and so arranged relative to the closure as to form a chute in combination therewith and a slidable closure for the 20 opening carried by the door, said closures being arranged to close said discharge opening alternatively, and the last mentioned closure adapted to normally hold the said aprons in an upright position.

25 2. A device of the character described including a hingedly mounted support; a door slidably mounted thereon and having a discharge opening therethrough; suitable cleats, secured on said door, one on each side 30 of the opening and having two lengthwise grooves on the inner side thereof; a vertically sliding closure movable in one set of

35 said grooves and arranged to close said opening; a closure hinged to said door near its base and also arranged to close said opening, folding aprons hinged at one side to said last mentioned closure and having their other edges free, means carried by said free edges disposed so as to engage in said 40 grooves, and the folding aprons being held normally in position, when the closures are open, by the said sliding closure.

3. A device of the character described including a car door slidably mounted upon a suitable support and having a discharge 45 opening therethrough; cleats carried by the door on each side of the opening and two lengthwise grooves on the inner sides thereof; a sliding closure, movable in one set of 50 said grooves and arranged to close the opening; a closure hinged to the door near its base and also arranged to close its opening; folding aprons hinged at one side to said last mentioned closure and having their other edges free, and ribs carried by said 55 free edges and arranged to engage in either of said grooves.

In testimony whereof I have signed my name to this specification in the presence of two subscribing witnesses.

RUDOLPH CHARLES MILLER.
